(57) **CLAIM**

The ornamental design for a dispenser mounting hole pattern, as shown and described.

DESCRIPTION

FIG. 1 is a perspective view of an exemplary dispenser providing context for the new design;

FIG. 2 is a front elevational view of the exemplary dispenser providing context for the new design;

FIG. 3 is a back elevational view of the dispenser mounting hole pattern of the dispenser;

FIG. 4 is a right side elevational view of the exemplary dispenser providing context for the new design;

FIG. 5 is a left side elevational view of the exemplary dispenser providing context for the new design;

FIG. 6 is a top plan view of the exemplary dispenser providing context for the new design; and,

FIG. 7 is a top bottom view of the exemplary dispenser providing context for the new design.

The broken lines shown in the figures represent portions of the dispenser mounting hole pattern that form no part of the claimed design.
